US00D729142S

(12) **United States Design Patent**
Ziaylek et al.

(10) **Patent No.:** **US D729,142 S**
(45) **Date of Patent:** **** May 12, 2015**

(54) **REMOTE EQUIPMENT STORAGE APPARATUS FOR AN EMERGENCY VEHICLE**

(71) Applicant: **Michael P. Ziaylek**, Yardley, PA (US)

(72) Inventors: **Michael P. Ziaylek**, Yardley, PA (US);
W. Brian McGinty, Huntingdon Valley, PA (US)

(73) Assignee: **Michael P. Ziaylek**, Yardley, PA (US)

(**) Term: **14 Years**

(21) Appl. No.: **29/442,769**

(22) Filed: **May 10, 2013**

(51) LOC (10) Cl. **12-06**

(52) U.S. Cl. USPC **D12/223**

(58) **Field of Classification Search**

USPC D12/1, 223; 414/462, 680, 917; 280/4;
182/127

See application file for complete search history.

Primary Examiner — Sheryl Lane

(74) Attorney, Agent, or Firm — Fox Rothschild LLP;
Richard C. Woodbridge; Glenn M. Massina

(57) **CLAIM**

The ornamental design for a remote equipment storage apparatus for an emergency vehicle, as shown.

DESCRIPTION

FIG. 1 is a front three-quarter perspective view embodying our new design;

FIG. 2 is a front plan view;

FIG. 3 is a rear plan view;

FIG. 4 is a side plan view taken from the right;

FIG. 5 is a side plan view taken from the left;

FIG. 6 is a top plan view; and,

FIG. 7 is a bottom plan view.

1 Claim, 6 Drawing Sheets
